J. H. WEISBROD.
BOX CAR CONSTRUCTION.
APPLICATION FILED JULY 26, 1916.

1,244,807.

Patented Oct. 30, 1917.

UNITED STATES PATENT OFFICE.

JACOB H. WEISBROD, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

BOX-CAR CONSTRUCTION.

1,244,807.

Specification of Letters Patent. Patented Oct. 30, 1917.

Application filed July 26, 1916. Serial No. 111,407.

To all whom it may concern:

Be it known that I, JACOB H. WEISBROD, residing at St. Louis, Missouri, and being a citizen of the United States, have invented 5 certain new and useful Improvements in Box-Car Constructions, of which the following is a full, clear, and exact description, such as will enable others skilled in the art to which it appertains to make and use the 10 same, reference being had to the accompanying drawings, which illustrate the preferred form of the invention; though it is to be understood that the invention is not limited to the exact details of construction shown 15 and described, as it is obvious that various modifications thereof within the scope of the claims will occur to persons skilled in the art.

In said drawings:

20 Figure 1 is a view partly in elevation and partly in section of approximately one half of a box car equipped with the present invention.

25 Fig. 2 is a transverse sectional view, the portion of said view at the right being taken on the line 2—2 of Fig. 1 looking in the direction indicated by the arrow, and the section at the left of Fig. 2 being taken substantially midway the length of the car.

30 Fig. 3 is an enlarged fragmentary detail sectional view showing the connection of the side sill, floor, side sheathing, etc., as shown at the lower right hand side of Fig. 2.

Fig. 4 illustrates a modification of the 35 construction shown in Fig. 3.

Figs. 5 and 6 illustrate further modifications all as hereinafter described.

Fig. 7 is an enlarged fragmentary detail 40 hereinafter particularly described.

The object of the present invention is to provide in a metallic underframe and wood superstructure box car, means for supporting short floor boards extending from the web of one side sill at one side of the car 45 to the corresponding side sill at the opposite side of the car, and in the same construction to provide means for connection thereto of the lower end of wood side sheathing forming the outer shell of the car body.

Other objects are to provide in a car of the class described, deep plate girder center sills with continuous cross bearers intersecting said sills and extending from side 50 sill to side sill, thereby serving as support-

ing means for the said sills and transmitting the load therefrom to the center sills.

Other features of advantage are the result of economy of manufacture and simplicity in assembling the parts.

Referring particularly to the drawings, A indicates one of the center sills which, as will be noted in Fig. 1, is of the plate girder type and extends from beyond the bolster at one end to a corresponding point at the 60 opposite end of the car. Intersecting the spaced center sills, there being two of such center sills, are continuous cross bearers B which extend through the webs of and are connected with said center sills by angle 65 plates C and D, said cross bearers extending outwardly to and below the side sills 2, as best shown at the left of Fig. 2.

Associated with the parts enumerated, 70 are bolsters E of a conventional type comprising bolster center filler castings F, web plates G and top and bottom cover plates K, K, which bolsters, like the cross bearers B, extend outwardly below the side sills 2, as best shown at the right of Fig. 2.

The said side sills are preferably formed of rolled Z-shaped sections disposed as shown in Figs. 3 and 4 and in the preferred construction short angles 10 are riveted at intervals to the webs of the side sills 80 and are so disposed that the bottom legs of said angles 10 serve as laterally projecting flanges for said side sills.

The angles 10 are disposed at convenient intervals throughout the length of the side 90 sill and are positioned in vertical alignment with the post pockets 4 employed with the conventional side framing of box cars.

In the modifications shown in Figs. 5 and 6, the side sills 2^a are of channel shape in 95 cross section. As shown in Fig. 5 short angles 8 are secured to the web of the sill 2^a, said angles having bottom flanges projecting inwardly, that is, toward the center of the car, upon which flanges rest floor nailing-strips 6, the latter being bolted in position by vertical bolts 6^a extending through said floor nailing-strips 6 and through the inwardly projecting horizontal flange of said angle 8, which is, in effect, an inwardly disposed sill flange. In the modification of Fig. 6 the angle 9 is substantially co-extensive with the length of the floor which latter rests upon the horizontal inwardly disposed leg of said angle 9 and is 100 105 110

secured thereto by bolts 9^a, the floor nailings strips in this modification being omitted. To the floor nailings strips 6, which are shown in Figs. 3, 4 and 5, the short floor boards 5, forming the floor of the car, are secured by spikes or any suitable fastening means, and it is to be noted that the floor boards 5 in the type of construction illustrated, need only be of a length to span the space between the webs of the side sills. In the type of construction illustrated in Fig. 6, the side sill is of channel form and like that of Fig. 5, the integral flanges of said channel are outwardly disposed, and in Fig. 15 an angle 9 is riveted to the web of said channel, with the horizontal leg of said angle disposed relatively intermediate the top and bottom flanges of said side sill, said horizontal leg of the angle 9 extending inwardly and serving as a direct supporting means for the floor 5 illustrated in said figure, which floor is secured to the angle 9 by bolts 9^a extending through the floor 5 and through the inwardly disposed flange of the angle 9, thus eliminating, in this modification, the floor nailings strips 6 common to the other figures.

Resting upon the bottom flange of the channels 2^a of Figs. 5 and 6, and upon the short angles 10 of the preferred construction of Fig. 3, are side sheathing nailings strips 12.

Resting upon the top flanges of the side sills 2 and 2^a are post pockets 4, through which extend framing rods 14, said rods extending vertically in the modification shown in Fig. 4, through the post pockets, the top flange of the sill 2, and through said nailings strip 12, a washer 15, of large area, resting under said nailings strip 12, and being held in position by nuts 16 on the lower ends of said rods 14, thereby supporting said nailings strip 12, in the modification of Fig. 4, directly upon said framing rods. In the preferred construction, however, short angles 10 are disposed at convenient intervals coincident with the locations of the post pockets, and the framing rods 14 extend through the casting of which said post pockets are a part intermediate the pocket for the vertical post 17 and that for the diagonal post or brace 18, as best shown in Fig. 7, said framing rod extending thence through the top flange of the sill 2, through the side sheathing nailings strip 12 and through said short angles 10, said rods being provided with nuts 16, as shown in Fig. 4.

In the modifications of Figs. 5 and 6, the framing rods 14 pass downwardly through the post pockets 4, thence through the top flanges of the channel-shaped sills 2^a, through the side sheathing nailings strip 12, and through the bottom flange of said side sills 2^a, nuts 16 being provided at the bottom ends of said rods.

Employing the framing rods 14 as described and projecting them through the side sheathing nailings strip, obviates the necessity for using a large number of bolts which would otherwise be required to secure 70 said nailings strips in position and disposing said nailings strips beneath the top flanges of the side sills, provides protecting means for such nailings strips and prevents the rapid disintegration thereof, which would 75 otherwise occur.

Likewise, the angles 8, 9 and 10 being riveted to the vertical webs of the side sills, as shown, provide reinforcements for said sills and in Fig. 3 the angles serve as rigid 80 anchoring means for the bottom ends of the framing rods 14, similar rigid anchoring means being provided in the modifications of Figs. 5 and 6 by the bottom flanges of the side sills 2^a of said figures. 85

What I claim is:

1. In combination, a metallic side sill having a vertical web and horizontal flanges, wood sheathing lapping said web, a sheathing nailings strip interposed between the outer side of said web and said sheathing, a framing rod projected through said sheathing nailings strip and one of said sill flanges, and a floor terminating within and supported by a flange projecting inwardly 95 from said sill web.

2. In combination in a railway car, metallic side sills each having a vertical web with connected horizontal flanges, a floor interposed between the webs of said sills and supported by flanges thereof, side-sheathing nailings strips disposed on the outer side of said sill web, and sheathing lapping said sheathing nailings strips.

3. In combination in a railway car, metallic side sills each having a vertical web with connected horizontal flanges, a floor interposed between the webs of said sills and supported by flanges thereof, side-sheathing nailings strips disposed on the outer side of 110 said sill web, sheathing secured to said sheathing nailings strips, and framing rods projected through said latter nailings strips and a flange of said sill.

4. In combination in a railway car, a metallic side sill having a vertical web with horizontal laterally extending flanges connected with said web, a wood - sheathing nailings strip below one of said flanges, a sheathing lapping and being secured to said 115 nailings strip, a floor supported by another of said flanges, and a framing rod extending vertically through said sheathing nailings strip and a flange of said sill.

5. In combination in a railway car, a metallic side sill having a vertical web with horizontal laterally extending flanges connected with said web, a wood - sheathing nailings strip below one of said flanges, a sheathing lapping and being secured to said 120

nailing-strip, a floor nailing-strip supported by another of said flanges, a floor resting on said floor nailing-strip and terminating at the inner side of said sill web, and means 5 securing said sheathing nailing-strip in position.

6. In combination, spaced metallic side sills each having a vertical web and an outwardly disposed upper flange, wood sheathing lapping said web, a sheathing nailing-strip interposed between the outer side of said web and said sheathing, a framing rod projected through said sheathing nailing-strip and one of said sill flanges, and a floor 10 extending between the inner faces of the webs of said side sills adapted to be positioned from above the latter and supported by flanges projecting inwardly from said sill webs.

20 7. In combination in a railway car, metallic side sills each having a vertical web with connected horizontal flanges, a floor interposed between the webs of said sills and supported by flanges thereof, side-sheathing 25 nailing-strips disposed on the outer side of said sill web, sheathing lapping said sheathing nailing-strips, and framing rods securing said nailing-strips in position.

8. In combination in a railway car, metallic side sills of Z-shape in cross section, each 30 having a vertical web with integral horizontal flanges, a floor interposed between the webs of said sills and supported by flanges thereof, side sheathing nailing-strips 35 disposed on the outer side of said sill web,

angles secured to said sill webs and supporting said nailing strips, sheathing secured to said sheathing nailing-strips, and framing rods projected through said latter nailing-strips and through said angles.

40

9. In combination in a railway car, a metallic side sill having a vertical web with horizontal laterally extending flanges connected with said web, a wood-sheathing nailing-strip below the upper of said flanges, 45 a sheathing lapping and being secured to said nailing strip, a floor supported by another of said flanges, and a framing rod extending vertically through said sheathing nailing-strip and the top flange of said sill. 50

10. In combination in a railway car, a metallic side sill having a vertical web with horizontal laterally extending flanges connected with said web, a wood-sheathing nailing-strip below one of said flanges, a 55 sheathing lapping and being secured to said nailing-strip, a floor nailing-strip supported by another of said flanges, a floor resting on said floor nailing-strip and terminating at the inner side of said sill web, post pockets 60 resting on the top flanges of said side sills and means securing said sheathing nailing-strip and said post pockets in position.

In witness whereof I have hereunto set my hand in the presence of two witnesses. 65

JACOB H. WEISBROD.

Witnesses:

OSCAR HOCHBERG,
BLASDEL SHAPLEIGH.
